United States Patent Office

Des. 221,189
Patented July 13, 1971

221,189

BOAT

Claudius E. Engh, 900 Donner Way,
Salt Lake City, Utah 84102

Filed Jan. 29, 1970, Ser. No. 21,143

Term of patent 14 years

Int. Cl. D12—06

U.S. Cl. D71—1

FIG. 4

FIG. 5

FIG. 1 is a side elevation view of a boat showing my new design;

FIG. 2, a front elevation view;

FIG. 3, a rear elevation view;

FIG. 4, a top plan view; and

FIG. 5, a perspective view taken from the front and above the boat.

I claim:

The ornamental design for a boat, substantially as shown and described.
